UNITED STATES PATENT OFFICE

153,505

DESIGN FOR A BUILDING

Harold W. Davis and Jack W. Weber,
Denver, Colo.

Application March 5, 1947, Serial No. 137,374

Term of patent 3½ years

(Cl. D13—1)

To all whom it may concern:

Be it known that we, Harold W. Davis and Jack W. Weber, citizens of the United States, residing at the city and county of Denver and State of Colorado, have invented a new, original and ornamental Design for a Building, of which the following is a specification, reference being had to the accompanying drawing, forming part thereof.

Figure 1 is a top plan view of the building, showing our new design. Figure 2 is a front elevation thereof. Figure 3 is an end elevation thereof. Figure 4 is a rear elevation thereof.

We claim:

The ornamental design for a building, as shown.

HAROLD W. DAVIS.
JACK W. WEBER.
